UNITED STATES PATENT OFFICE.

JOHN ETTLIN, OF KANSAS CITY, MISSOURI.

WINDOW-SCAFFOLD.

SPECIFICATION forming part of Letters Patent No. 350,924, dated October 19, 1886.

Application filed July 29, 1886. Serial No. 209,475. (No model.)

To all whom it may concern:

Be it known that I, JOHN ETTLIN, of Kansas City, in the county of Jackson and State of Missouri, have invented certain new and 5 useful Improvements in Window-Scaffolds; and I do hereby declare the following to be a full, clear, and exact description of the invention, such as will enable others skilled in the art to which it appertains to make and use 10 the same.

My invention relates to an improvement in window-scaffolds.

The object of the same is to provide a scaffold which can be easily and quickly adjusted 15 to a window-sill.

A further object is to provide a scaffold which can be folded and packed in a small space.

A still further object is to provide means 20 whereby the scaffold may be adjusted to window-sills of different widths.

With these ends in view my invention consists in certain features of construction and combinations of parts, as will be hereinafter 25 described, and pointed out in the claims.

In the accompanying drawings, Figure 1 is a vertical sectional view of my device, showing the chair or scaffold adjusted to a window-sill. Fig. 2 is a detached view of the clamping device. Fig. 3 is a detached view, in section, of one of the sliding sections. Fig. 4 is a view of one of the metal plates *d*, and Fig. 5 is an enlarged view of the mechanism for locking the side arms to the chair-back.

35 A represents a window-sill of any ordinary construction; B, the base of my improved device, the end pieces, *a*², of which are provided on opposite faces with grooves *b*, running longitudinally throughout a portion of their length.

40 Secured to the end pieces, *a*², of the base B and engaging the grooves *b* are the sliding sections C, the inner ends of which project downwardly below the top of the sill, and are each provided with a clamp-screw, *c*, which is adapted 45 to be forced against the inside of the window-sill and hold the inner end of the scaffold or chair in a firm position. Secured to the upper surfaces of said sliding sections C are thumb-screws D, the free ends of which enter 50 holes *a*³, formed in the face-plate *d*, secured to the upper surfaces of the end sections, *a*², of the bases in any ordinary manner.

Attached to the under side of the bases B, and near its outer edge, are two brackets opposite each other, and adapted to rest on the 55 sill and support the outer edge of the base.

The two end sections, *a*², of the base B of the scaffold are connected together by slats *b*', which serve as a floor or seat to the scaffold.

E E' are two uprights, each of which is secured to its respective end sections, *a*², of the base in swinging adjustment, and project below the same, and terminate in a head or extended bearing E², which is preferably covered with rubber for the purpose of giving it 65 a firm hold, and at the same time prevent the disfigurement of the sill or wall.

At suitable distances on the uprights E E', and connecting the same, are bent strips *e*, which serve as a back or guard for a person sitting in or standing on the base or bottom of 70 the chair or scaffold.

Pivotedly secured to the base B are the arms or braces K, each of which terminates in ratchet-teeth *h*, and are connected together by means 75 of a rod, *h*'. The ratchet-teeth *h* engage pins G, secured to the inner faces of the uprights E E', and serve as a lock for the chair-back. Rigidly secured above these pins G are the springs F, which latter hold the teeth in contact with the pins and prevent accidental displacement of the arms. The rod *h*', being behind the uprights E E', prevents the chair or scaffold back from falling backwardly.

When it is desired to remove the scaffold, 85 the ratchet-teeth *h* are disengaged from the pin G, and the chair-back, then having nothing to support it, is free to be tilted inwardly, which movement carries the lower ends of the uprights away from the sill and leaves the device 90 free to be removed.

It is evident that slight changes might be resorted to in the form and arrangement of the several parts without departing from the spirit and scope of my invention—for instance, 95 the parts might be made of light and durable metal; hence I do not wish to limit myself to the exact construction herein set forth, but consider myself at liberty to make such changes that fall within the scope and spirit of my invention.

Having fully described my invention, what I claim as new, and desire to secure by Letters Patent, is—

1. The combination, with a base, one end of which is adapted to bear against the wall below the inner edge of the sill, of a tilting back, the lower edge of which engages the outer face 5 of the wall or sill below the lower edge of the latter, and devices for locking the tilting back in position.

2. The combination, with an extensible base, one edge of which is adapted to engage the 10 wall below the inner edge of the sill, of a tilting back, the lower edge of which engages the sill or wall below the base, and devices for locking the back in an upright position.

3. The combination, with a base, clamps secured to the inner edge thereof, and brackets 15 secured to the lower face of said base, of the tilting back, the lower edge of which engages the outer face of the wall below the base, and devices for locking the back in an upright position.

4. The combination, with a base having

grooved end pieces, the sliding sections, thumb-screws for locking the sliding pieces to the end pieces, and the clamping-screws, of the tilting back extending below the base and 25 devices for locking the back in an upright position.

5. The combination, with a base having devices for locking one edge thereof to the sill, of the tilting back, the lower edge of which is 30 arranged to engage the wall below the sill, and having pins and springs, and the arms having teeth for engaging the pins, substantially as set forth.

In testimony whereof I have signed this 35 specification in the presence of two subscribing witnesses.

JOHN ETTLIN.
